(57) **CLAIM**

The ornamental design for a garage door panel planter box, as shown and described.

DESCRIPTION

FIG. 1 is a top, front perspective view of a first embodiment of a garage door panel planter box;

FIG. 2 is a front view of the garage door panel planter box of FIG. 1;

FIG. 3 is a rear view of the garage door panel planter box of FIG. 1;

FIG. 4 is a right-side view of the garage door panel planter box of FIG. 1;

FIG. 5 is a left-side view of the garage door panel planter box of FIG. 1;

FIG. 6 is a top view of the garage door panel planter box of FIG. 1;

FIG. 7 is a bottom view of the garage door panel planter box of FIG. 1;

FIG. 8 is top, front perspective view of the garage door panel planter box of FIG. 1, with environmental subject matter;

FIG. 9 is a top, front perspective view of a second embodiment of the garage door panel planter box;

FIG. 10 is a front view of the garage door panel planter box of FIG. 9;

FIG. 11 is a rear view of the garage door panel planter box of FIG. 9;

FIG. 12 is a right-side view of the garage door panel planter box of FIG. 9;

FIG. 13 is a left-side view of the garage door panel planter box of FIG. 9;

FIG. 14 is a top view of the garage door panel planter box of FIG. 9;

FIG. 15 is a bottom view of the garage door panel planter box of FIG. 9; and,

FIG. 16 is a top, front perspective view of the garage door panel planter box of FIG. 9, shown with environmental subject matter.

(Continued)

The broken line drawings of the plants shown in FIG. 8 and FIG. 16 are for the purpose of illustrating environmental subject matter and form no part of the claimed design. All other broken lines in FIGS. 1-3, 6-11 and 14-16 represent portions of the garage door panel planter box that form no part of the claimed design.

1 Claim, 16 Drawing Sheets
